(57) **CLAIM**

The ornamental design for an outdoor timer, as shown and described.

DESCRIPTION

FIG. 1 is a top perspective view of the outdoor timer according to our design;

FIG. 2 is a rear elevation of our design shown inverted;

FIG. 3 is a top view of our design;

FIG. 4 is a right side view of our design;

FIG. 5 is a left side elevation of our design; and,

FIG. 6 is a front elevation of our design shown inverted.

The broken line shown in FIG. 2 is for illustrative purposes only and forms no part of the claimed design.
